UNITED STATES PATENT OFFICE.

PINCUS FARBER, OF NEWARK, NEW JERSEY, ASSIGNOR TO SONORA PHONOGRAPH CORPORATION, A CORPORATION OF NEW YORK.

JIG.

1,294,643.

Specification of Letters Patent.

Patented Feb. 18, 1919.

Application filed May 8, 1917. Serial No. 167,378.

To all whom it may concern:

Be it known that I, PINCUS FARBER, a citizen of the United States, and a resident of the city of Newark, county of Essex, and State of New Jersey, have invented a certain new and useful Jig, of which the following is a specification.

My invention relates to jigs for locating the position of one part of a mechanism relatively to another part, and more particularly for locating, on the outside of the cabinet, the position of the opening through which the hub of the winding crank of a talking machine is inserted to engage the winding shaft of the motor, and also for locating, on the outside of the cabinet, the location of the opening through which passes the rod for operating the tone modifier when such is employed.

In the manufacture of talking machines, the motor is constructed in a machine shop and suspended on the underside of the motor board, and the holes for the screws which will secure the board in the cabinet, are bored at the desired points. The horn is made by a horn maker who also produces a hollow block which is to connect the small end of the horn with the tone-arm of the machine. The horn maker also forms a recess at some point in the block. This recess is for the reception of a sliding damper or tone modifier. Before the horn is finished, a hole is bored in one side of the box in line with the damper recess. The cabinet or ornamental covering for the working parts of the machine, is built by a model maker. The horn is secured in the lower part of the cabinet with the block in one corner. The motor board is now placed in the cabinet over the horn and block. The board has an opening in line with the vertical bore of the block, and an opening through which the turn-table shaft of the motor projects. Before the board is placed in position, careful measurement of the locations of the damper rod opening and of the winding shaft are taken and the cabinet maker must mark off on the outside of the cabinet points in axial alinement with the opening and the winding shaft. The holes for the crank and damper rod are now bored from the outside.

The proper locations of the holes on the sides of the cabinet are difficult to ascertain, and when the holes are bored it is found that about ten per cent. of them are not in

proper position relatively to the shaft and rod opening, and this necessitates boring new holes and plugging up those first made. The cabinet is spoiled and must be sold, if at all, 60 as damaged goods.

The objects of my invention are to obviate the necessity for measuring the parts to locate winding shaft and damper rod opening, to make certain the positions of the 65 holes to be bored, to provide devices which can be manipulated by unskilled persons, and to expedite the work of the manufacturer.

These and further objects will more fully 70 appear in the following specification and accompanying drawings considered together or separately.

I have illustrated my invention in the accompanying drawings, in which like parts 75 are designated by similar reference characters in all of the figures, and in which,—

Figure 1 is a plan view of a talking machine cabinet with the motor board in place and with the device for locating the damper 80 rod opening in position, parts of the board being broken away;

Fig. 2 is a section on the line 2—2 of Fig. 1;

Fig. 2^a is a detail sectional view showing 85 the damper in position;

Fig. 3 is a plan view of a motor board with a device for locating the position of the winding shaft of the motor in position, parts being broken away to show the winding 90 shaft; and

Fig. 4 is a side elevation of the same with parts broken away.

My invention comprises two appliances, one for locating the position of the damper 95 rod opening, and another for locating the position of the winding shaft.

In the drawings, 1 designates a box like cabinet having sides 2 and 3, front and back members and a bottom. The cabinet 100 is provided with a ledge 4 on which the motor board 5 rests. To the underside of the board is secured a motor 6. In the embodiment illustrated, I show an ordinary spring motor having a spring drum 7 carrying a spur wheel 8 which is engaged by a spur pinion 9 carried on the shaft 10. The shaft carries a pawl 11 which is engaged by a ratchet on the motor frame to prevent the shaft from turning backward. A vertical shaft 12 geared to the spring drum through a governor, (not shown), projects 110

through the motor board and is adapted to carry the usual turn-table (not shown). The motor board is provided with holes 13 for the reception of screws by means of which 5 the board may be secured to the ledge 4.

A horn 13^a is disposed within the cabinet, and its rear end communicates with the bore 14 of a block 15 secured in the cabinet and engaging the under side of the motor board 10 which has an opening 16^a in axial alinement with and communicating with the bore 14. The upper part of the block is provided with a horizontal recess 16. The recess is wider than the diameter of the bore and extends 15 through the major portion of the top of the block. A hole 17 is bored in the block at the head of the recess and in radial alinement with the center of the bore.

It now becomes necessary to bore a hole 20 18 in the side 3 in axial alinement with the hole 17. The hole 18 must be bored from the outside and in order to indicate on the outside of the side member 3 the exact axial location of the hole 17, I employ the following 25 instruments:—

A U shaped frame 19 is provided with an inturned foot 20 having a reduced extremity 21. The extremity 21 is of a diameter to fit snugly in the hole 17, and its length is 30 not greater than the thickness of the block at that point. Carried on the other leg of the frame 19, in axial alinement with the foot 20, is a bearing 22 in which slides a rod 23 having a sharpened extremity 24. 35 Near the pointed end, the rod is provided with a groove in which is a split ring 25 of spring material. The ring will prevent the withdrawal of the rod from the bearing. At its opposite end, the rod has a knob 26. 40 and between the knob and bearing is disposed a spring 27 to normally hold the rod in its retracted position. The combined lengths of the foot 20 and extremity 21 are less than the diameter of the bore 14, so that 45 the foot may be inserted in axial alinement with the hole 17 even when the motor board is in position.

The operation is as follows:—

The frame 19 is placed in position with 50 the extremity of the foot 20 in the hole 17. The bar 27 is always in axial alinement with the foot, and when the knob is moved toward the cabinet, the pointed extremity 24 will make a punch mark on the outside of the 55 side 3, and when a hole is bored with that mark as a center, it will be in axial alinement with the hole 17, and when the damper 28 is placed in position in the recess 16, its operating rod 29 will pass through the 60 alined openings.

When the motor board is placed within the cabinet and resting on the ledge 4, it is necessary that a hole be bored in the side 2 in axial alinement with the winding shaft

10 in order that the winding crank may engage the shaft. 65

In order to indicate on the outside of the cabinet the exact axial location of the winding shaft, I employ a jig consisting of an elongated arm 30 having a right angle extension 31. Carried on the arm 30 is a slide 32 which may be clamped to the arm by means of a screw 33. The slide has an opening 34 of a size sufficient to fit over the reduced extremity of the turn-table shaft 12, 75 and may be clamped to the shaft 12 by means of a screw 35.

A second slide 36 is carried by the arm 30, and may be clamped thereto by means of a screw 37. The slide 36 has a tubular extension 38 in which works a plunger 39 having a foot 40. A toe 41 projects from the under side of the foot. A spring 42 tends to move the plunger outward, and a screw 43 secures the plunger in the desired position. 80

Mounted on extension 31 is a slide 44 which carries a sliding bar 45. The slide 44 may be clamped to the extension 31 by means of a screw 46, and the bar 45 is held in the desired position by a screw 47. A bearing 48 is carried on one end of the bar 45, and in the bearing is slidably mounted a rod 49 having a pointed extremity 50 at one end and a knob 51 at the other. Between the bearing and knob, a spring 52 is disposed for the purpose of normally withdrawing the rod 49. A ring 53 near the pointed end of the rod prevents the rod from being entirely withdrawn. 95

The slides 32, 36 and 44 make the device 100 adjustable for any size talking machine, and the adjustable plunger 39 will provide for differences in the height of the top of the shaft 12 above the motor board.

Before the motor board and motor are placed in the cabinet, the opening 34 will be placed over the end of the turn-table spindle or shaft. The slide 36 will be moved until the toe 41 can be placed in one of the screw holes, and the slide will be clamped in position. The slide 44 and bar 45 are now manipulated to such positions that the rod 49 can be moved inward until its point comes in contact with the center of the winding shaft 10. The rod 49 will now be in axial alinement with the shaft. The slide 44 is now clamped to the extension 31 and the bar 45 is clamped in the slide. The spring 52 will withdraw the rod from engagement with the shaft 10. The device may now be 110 removed from the motor board and the latter placed in position in the cabinet. The jig will now be placed in position with the opening 34 over the turn-table shaft, and the toe 41 resting in the same screw hole it engaged before. The rod 49 is again in axial alinement with the winding shaft and when it is pushed inward the pointed extremity. 125

will mark the side member 2 and a hole bored with that mark as a center will be in axial alinement with the winding shaft.

While I have shown, described and claimed my improved device in connection with a talking machine, I desire to have it understood that I do not wish to limit myself to such use, as the apparatus is capable of other uses.

In accordance with the provisions of the patent statute, I have described the principle of my invention together with the apparatus which I now consider to represent the best embodiment thereof, but I desire it understood that my invention is not confined to the particular form of apparatus herein shown and described, and, therefore, I claim broadly the right to employ all equivalent instrumentalities coming within the scope of the claims, and by means of which objects of my invention are attained, and the new results accomplished, as herein set forth, as it is obvious that the particular embodiment herein shown and described is only one of many that can be employed to attain these objects and accomplish these results.

Having now described my invention, what I claim and desire to secure by Letters Patent is:

1. An apparatus of the character described, comprising means for engaging a device, said means including a frame carrying a member for engaging a predetermined point of a desired object, an adjustable marker carried by the frame whereby a portion of the device may be located, and means whereby the marker will indicate a point in alinement with a desired portion of the device.
2. An apparatus of the character described, comprising a fitting adapted to engage a turn-table shaft, of a device having a screw hole and a winding shaft, a rod

slidably mounted in the fitting, means for securing the rod in the fitting, a slide movable on the rod, means for securing the slide to the rod, means on the slide for engagement with a screw hole, a second slide and means for securing it to the rod, an arm adjustable in the second slide, a marker carried by the arm, whereby, when the fitting is in engagement with the turn-table shaft and the slide is resting in the screw hole, the marker may be brought into axial alinement with said winding shaft, whereby the marker may be caused to engage the side of a part intervening between said winding shaft and the marker, and indicate thereon a point in axial alinement with said winding shaft.

3. A device of the character described, comprising a frame having means adapted to engage an object, a plurality of slidable members carried by said frame, means for adjustably holding said members, a marker having means permitting it to be brought into, and indicate a point in, axial alinement with a desired portion of the object.

4. A device of the character described, comprising a frame having means adapted to engage an object, a plurality of slidable members carried by said frame, means for adjustably holding said members, a marker having means permitting it to be brought into axial alinement with a desired portion of the object whereby the marker may be caused to engage the side of a part intervening between the object and the marker, and indicate on the part intervening a point in axial alinement with the object.

This specification signed and witnessed 80 this 5th day of May, 1917.
